DESIGN FOR A SANDING BLOCK

Louis Gerlinger, Salem, Oreg.

Application August 11, 1948, Serial No. 148,050

Term of patent 3½ years

(Cl. D37—1)

To all whom it may concern:

Be it known that I, Louis Gerlinger, a citizen of the United States, residing at Salem, in the county of Marion and State of Oregon, have invented a new, original, and ornamental Design for Sanding Block, of which the following is a specification, reference being had to the accompanying drawing, forming part thereof.

I claim:

The ornamental design for a sanding block, as shown.

LOUIS GERLINGER.
